APPARATUS FOR CASTING SHEETS OR FILMS

Ernest Bleibler, Ghent, Belgium, assignor to Sylvania Industrial Corporation, Fredericksburg, Va., a corporation of Virginia

Application November 10, 1934, Serial No. 752,479
In Great Britain November 6, 1933

9 Claims. (Cl. 18—15)

This invention relates to an apparatus for casting sheets and films from viscose and the like.

It is an object of this invention to ensure that the viscose flowing to the pouring slit of the hopper is continuously renewed with certainty, all parts thereof passing from the point where it enters to the slit of the hopper, without any stagnating parts of it being able to coagulate and so give rise to the choking up of the apparatus or other hindrances to the working thereof.

It is a further object of the invention to enable the viscose, which is supplied under the pressure of the viscose pump or by other means, e. g. compressed air, to tranquilize itself and to afford to gas or air opportunity to separate and collect apart from the viscose, so that the viscose inside the hopper space is completely free from gas or air.

Another object of the invention is to give allowance for the varying amount of shrinking which takes place over the width of the band regenerated from the viscose.

It is a further object of the invention to supply the viscose to the hopper without using any movable parts in the conduit, while the hopper itself is tiltable.

Still a further object of the invention refers to means which permit to observe accurately and to adjust the pressure gauge of the viscose.

According to the invention the casting apparatus for sheets or films is characterized by the fact that within the hopper above the pouring slit there are arranged conduit means for supplying the viscose in an ascending stream or streams, a free space being arranged in the upper part of the hopper to which upper part the viscose is delivered, the said conduit means exposing the surface of the viscose to the space within the said chamber before the viscose sinks down to the extruding slit, whereby air or gas included in the viscose separate into said space. Thus, the viscose is continuously renewed with certainty, and without any risk of any stagnating parts being able to coagulate and thus to choke up the apparatus.

This advantageous structure for feeding the viscose is assisted if, according to a preferred constructional form of the subject-matter of the invention, the conduit means terminate in a partition which extends towards the highest point of the hopper space.

The viscose, which is supplied under the pressure of the viscose pump or other means, e. g. compressed air, is able to tranquilize itself and gas or air are afforded opportunity to separate

and collect in the highest part of the hopper space, so that the viscose inside the hopper space which is really bounded by the partition is completely free from gas and air.

It is preferable to employ as a casting apparatus one made of a non-rusting material for example, as is known per se. Preferably also the outlet slit is adjustable in respect of its width, as hitherto known, and moreover, is adjustable in respect of its shape. In this way, the varying amount of shrinkage which takes place over the width of the band regenerated from the viscose can be allowed for. In the embodiment of this part of the invention one or both lips of the hopper are made adjustable transversely so as to enable the width of the slit to be regulated, while for the purpose of regulating the shape, one or both lips of the hopper are made to bend, as will hereinafter be more particularly described.

If the casting apparatus be made to oscillate about the hollow shaft which serves simultaneously to supply the viscose, important advantages are gained inasmuch as the viscose delivering conduits of the hopper can be packed in a convenient manner by means of the usual packings. The additional advantage is also gained that no moving parts are necessary to supply the viscose to the casting apparatus. By adjusting the adjustable lip and suitably tilting the hopper it is possible without any complicated adjusting means to make allowance for the particular conditions necessary in respect of the thickness and velocity of the sheet or film to be coagulated and issuing from the casting apparatus.

This exact adjustment of the thin film of viscose issuing from the casting apparatus can be still further assisted if in the further development of the present invention the hopper be provided at its highest point with a chamber for the separation of air or gases from the viscose and provided preferably with sight holes. This chamber may serve, according to another embodiment of this invention, in particular for the reception of an intermediate fluid, inert in particular towards viscose and leading through a pipe to the pressure gauge. By the interpolation of an intermediate medium between the viscose and the pressure gauge the advantage is gained that the pressure of the viscose can be accurately measured and therefore adjusted at any time, in contra-distinction to arrangements in which the viscose itself acts on the pressure gauge. In this arrangement there is risk that should there be any leakage between the viscose and the pres-

5

sure chamber the viscose will get into the pressure gauge or into the guard liquid, e. g. oil for the pressure gauge and will stay there and as the viscose does not run but remains quiescent it 5 will easily coagulate and render the pressure gauge useless especially in summer time. The interpolation of the inert fluid between the viscose and the pressure gauge therefore prevents such a sensitive instrument as the pressure gauge 10 having to be used directly over the coagulation bath and such wear and tear of the gauge is avoided. The interpolation of an inert fluid between the viscose and the pressure gauge consequently permits the pressure of the viscose being 15 accurately observed while the machine is at work, so that it can be accurately adjusted to the rate at which the machine is to work, to the width of the outlet slit, to the speed at which it issues therefrom, to the composition, the ripeness and 20 toughness of the viscose and also to the temperature of the viscose and the precipitating bath including the composition of this latter.

The invention further comprises a safety valve and pressure gauge consisting of a manometric vessel 25 containing an observation liquid, such vessel containing two ascension pipes staggered relatively to each other vertically, of which one opens near the bottom of the manometric vessel and at the bottom of an upper vessel, the second, 30 of glass or transparent material or the like, opens as a measuring pipe below and in the vicinity of the arbitrary level in the manometric vessel and in the upper part of the upper vessel, which has in this upper part an air outlet opening. 35 The invention will be best understood on referring to the drawings affixed to my specification and forming part thereof which illustrate the invention as embodied in a number of constructions. It will be readily understood, however, 40 that my invention is by no means limited to these constructions and that the scope of my invention and the ambit of my appended claims extends to any construction incorporating the broad principle underlying my invention.

45 In the drawings:

Fig. 1 shows in longitudinal section and

Fig. 2 in transverse section, the spinning nozzle according to this invention.

Fig. 3 shows in vertical section a constructional 50 example of a pressure indicating device with a safety valve.

Fig. 4 shows, diagrammatically, a form of the adjustable hopper outlet according to this invention.

55 Figs. 5 and 6 show in transverse section and elevation from below a constructional form for the adjustment of the outlet slit both as to width and shape, and

Fig. 7 shows a detail.

60 The casting apparatus is denoted by 11. The upper hopper chamber is constructed in a dome-like shape by suitable formation of the upper boundary wall 38 of the hopper and rises towards the centre and upwards, the viscose being delivered to the upper part thereof. The lips of the casting apparatus of which both or only one are movable transversely and/or bendable as will be subsequently described with reference to Figs. 4 to 7, which are preferably of a non-rusting material, are denoted by 14. The pipes 12, 13 are inserted in suitable sleeves 15, which may be provided with packing devices 17, and thus form a hollow shaft about which the hopper 11 can be tilted. In the hopper chamber below the upper 75 pipes 12, 13 are provided conduit-forming par-

titions 31 rising obliquely towards the centre of the cap or dome-like upper part of the hopper, so that the viscose entering from the pipes 12, 13 flows over the partitions 31 towards the central upper part of the hopper, is tranquilized on its way thereto and air or gas bubbles separate during this period and collect in the upper part of the hopper. The viscose, freed from gas and air bubbles distributes itself from the opening 32 between the partitions 31 uniformly over the width 10 and length of the hopper and flows in a homogeneous gas and air free mass and at a uniform rate of speed to the opening 29 of the hopper (see Fig. 2). Along this path no corners are present to arrest the even flow of the viscose, nor are there any recesses into which it could run and give rise to choking up of the machine or other disturbances in the flow of the viscose to the opening of the hopper.

At the highest point of the nozzle a cylindrical chamber for example is provided, in which the gas or air contained in the viscose can collect. This cylindrical chamber 18 may be provided with eight holes 26 on opposite sides thereof which may be closed by transparent panes of 25 glass, and which permit what is happening in the chamber 18 to be watched.

In a further development of the invention the chamber may serve for the reception of an intermediate fluid which is inert towards viscose, 30 such as air for example or another gas or even a suitable liquid which serves to connect the hopper space to a pressure gauge 24 through the pipe 23. To shut off this pipe a valve 22 is provided. At or in the vicinity of the highest point of the 35 upper part of the hopper and preferably at the foot of the chamber 18 an outlet 35 having a valve is provided by which the inert fluid contained in the chamber or even viscose should it be necessary, can be run off.

40 A pipe 26 with a valve 19 may serve to remove air or gas from the chamber 18 or to introduce the intermediate medium also or even to connect the chamber 18 to a second pressure gauge.

Fig. 3 shows a pressure gauge 25 such as is suitable for a casting apparatus particularly one according to this invention. This device permits of a simple connection being made with a safety valve. It consists of a manometric vessel 40, which is filled to a suitable height 41 with an indicating liquid such as coloured water for example. The manometric vessel has two ascension pipes 42, 43, the respective levels of which are staggered, so that the one 43, opens near the bottom 44 of the manometric vessel 40 on the 55 one hand and at the bottom of an upper vessel 56. The second ascension pipe 42 opens below and near the arbitrary level 41 of the manometric vessel on the one hand and on the other hand in the upper part 51 of the upper vessel. 60 This upper vessel has in its upper part also an air outlet opening 52. The ascension pipe 42 or both ascension pipes also are provided with a scale for reading off the pressure.

If now for any reason the pressure in the head 65 of the hopper rises, the level 41 falls below the lower mouth of the pipe 42, so that the intermediate medium, say air for example, can pass out of the pipe 23 directly into the ascension pipe 42 and now ejects the indicating liquid contained 70 therein upwards out through the upper openings 43. The liquid collects at the bottom of the upper vessel and flows through the pipe 43 back again. A baffle 53 arranged between the mouth 75 43 and the air outlet pipe 52 prevents the meas-

uring liquid from being ejected through the air outlet opening. The excess of pressure can now escape unimpeded through the ascension pipe 42, the mouth 48, and the air outlet 52. If the upper vessel be composed of glass or other transparent material, the process of ejection of the liquid can be watched and the man in charge of the hopper can therefore take precautionary measures at once.

- 10 In order to make allowance for the varying degree of shrinkage which takes place over the width of the band, Figs. 5 to 7 show an arrangement which permits of the outlet slit of the hopper being adjusted both as regards width and shape. 15 For example, the slit may be given the shape shown in Fig. 4, which allows of a larger quantity of viscose to pass at the middle than at the edges, so that at the end after the band has dried a uniform thickness of the band is obtained and 20 undesirable stresses at the edges are avoided.

In the example shown in Figs. 5 to 7 a transversely movable lip is arranged on the cheek 60 while the lip 63 of the cheek 61 can be bent. This transverse movement is produced by means of screws 65 operated by hand wheels 66 for example and which are adjustable by means of screw threads in a projection or a rib 67 on the cheek. The bolts 65 have on their other ends a round head 68, which rotates freely in a recess 69 in the lip 62, and is secured there by a bipartite rib or other covering 70, 71 which prevents it from moving out of place as shown on a large scale in Fig. 7.

The lip 62 is also secured by screws 73 which engage by screw threads in the flanges of the cheeks 60 and the stems of which pass through slots 74 in the lip 62, which permit of a transverse movement thereof.

To enable the lip 63 to bend it is made flexible, 40 its limb 78 being thin transversely and comparatively long vertically. This limb is produced by a recess or groove 80 in the foot 81 of the hopper wall 61. The groove or recess 80 is on the other hand bounded by a rigid rib 82 on the foot 81 of the wall opposite the limb 78 of the lip. Between the limb 78 of the lip and the rib 82 are placed tension screws 84 and clamping screws 85, which are arranged alternately in considerable number on the lip. By moving the lip 62 50 transversely and bending the lip 63 the width and shape of the outlet slit of the hopper can be adjusted as may be desired to correspond to the particular conditions and working requirements of the moment.

55 Since various modifications and different embodiments of the apparatus may be made without transcending the teachings of the invention, it is to be understood that the invention is not limited except as indicated in the appended claims.

I claim as my invention:—

1. In an apparatus for casting sheets or films, the combination of a hopper for a film-forming material having an extrusion slit in the lower portion thereof, said hopper being so constructed and arranged as to provide a gas-collecting means at the upper portion thereof above the film-forming material, and means for introducing film-forming material in an ascending stream into said hopper above said slit and below said gas-collecting means, whereby gas entrapped in the film-forming material may escape to said gas-collecting means before the film-forming material sinks down and passes through said extrusion slit.

2. In an apparatus for casting sheets or films, the combination of a hopper for a film-forming material having an extrusion slit in the lower portion thereof and a chamber positioned above and communicating with said hopper, and means for introducing the film-forming material into said hopper above said slit, said introducing means terminating adjacent the opening between said chamber and said hopper whereby gas entrapped in the film-forming material may escape to said chamber before the film-forming material sinks down and passes through said extrusion slit.

3. In an apparatus for casting sheets or films, the combination of a hopper for a film-forming material having an extrusion slit therein adjacent the lower portion thereof, said hopper being so constructed and arranged as to provide a gas-collecting means above the film-forming material in said hopper, and means for introducing the film-forming material into said hopper, said means comprising an upwardly-extending conduit terminating adjacent said gas-collecting means whereby gas entrapped in the film-forming material may escape to said gas-collecting means before the film-forming material sinks down and passes through said extrusion slit.

4. In an apparatus for casting sheets or films, the combination of a hopper for a film-forming material having an extrusion slit adjacent the lower portion thereof, said hopper being so constructed and arranged as to provide a gas-collecting means above the film-forming material in said hopper, an upwardly-extending partition in said hopper forming the inferior border of a conduit for the film-forming material in said hopper, said partition terminating adjacent said gas-collecting means, whereby gas entrapped in said film-forming material may escape to said gas-collecting means before the film-forming material sinks down and passes through said extrusion slit.

5. In an apparatus for casting sheets or films the combination of a hopper for a film-forming material having an extrusion slit at the lower portion thereof, an upper covering for said hopper, said upper covering having an upward extension defining a gas-collecting means communicating with the interior of said hopper, a conduit for introducing film-forming material extending upwardly through said hopper and terminating adjacent the lower portion of said gas-collecting means, whereby film-forming material introduced into said hopper through said conduit may release entrapped gases into said gas-collecting means before falling into said hopper.

6. In an apparatus for casting sheets or films, the combination of a hopper for film-forming material having an extrusion slit in the bottom thereof, said hopper being so constructed and arranged as to provide a gas collecting means at the upper portion thereof, means for introducing film-forming material into said hopper in an ascending stream to a point adjacent said gas-collecting means where said film-forming material may then sink into the lower part of said hopper, and means for indicating the pressure of film-forming material in said hopper, said means comprising a pressure gauge connected with said gas-collecting means and a fluid which is inert with respect to said film-forming material disposed between said gauge and the film-forming material in said hopper.

7. In an apparatus for casting sheets or films,

the combination of a hopper for film-forming materials being so constructed and arranged as to provide a gas-collecting means in the upper portion thereof, means for introducing film-forming materials into said hopper, said means extending upwardly through said hopper and terminating adjacent said gas-collecting means, the lower portion of said hopper walls terminating in lips defining an extrusion slit, which is adjustable with respect to width and shape.

8. In an apparatus for casting sheets or films, the combination of a hopper for film-forming materials being so constructed and arranged as to provide a gas-collecting means in the upper portion thereof, a conduit extending upwardly in said hopper and terminating adjacent said gas-collecting means and adapted to introduce film-forming materials into said hopper in an ascending stream, the lower portion of said hopper

walls terminating in lips defining an extrusion slit, at least one of said walls being flexible in part whereby it may be bent to vary the shape of the slit.

9. In an apparatus for casting sheets or films, the combination of a hopper for a film-forming material having an extrusion slit in the lower portion thereof, an upwardly-extending partition in said hopper between the upper and lower portions thereof, said partition forming the inferior border of a conduit which introduces film-forming material into said hopper, said partition terminating with an opening therein in the highest part thereof, wherethrough the film-forming material sinks down and passes to and through said extrusion slit, whereby gas entrapped in the film-forming material may escape to the space above said partition.

ERNEST BLEIBLER.
